METHOD OF MAKING HEAD LINING
LISTING SUPPORTS

Lawrence H. Heuer, Detroit, Mich.

Original application November 12, 1938, Serial
No. 240,198. Divided and this application
January 30, 1939, Serial No. 253,657

3 Claims. (Cl. 29—152)

This invention relates generally to the method of making head lining listing supports for use in vehicle body constructions and constitutes a division of my application filed November 12, 1938, bearing Serial No. 240,198.

One of the essential objects of the invention is to form the supports in such a way from flat stock that they may be bent readily without deformation to conform to the interior cross sectional configuration of the vehicle body structure to which they are applied.

Another object is to form the supports so that they will be lighter in weight and stiffer and stronger in construction than supports of the conventional type.

Another object is to employ an improved method that is economical and that insures uniformity in construction.

Other objects, advantages and novel details of construction of this invention will be made more apparent as this description proceeds, especially when considered in connection with the accompanying drawing, wherein:

Figure 1 is a perspective view of one of the supports embodying my invention before it is bent to conform to the cross sectional configuration of a vehicle body top;

Figure 2 is an elevation of the support after it has been bent to conform to the cross sectional configuration of a vehicle body top;

Figure 3 is an enlarged perspective view of one end of the support;

Figure 4 is a view similar to Figure 3, but showing the opposite side thereof;

Figure 5 is a cross sectional view taken substantially on the line 5—5 of Figure 2.

Referring now to the drawing, A is a support embodying my invention rolled from a single sheet of metal and having flattened ends 1 and 2, respectively, and an intermediate tubular portion 3.

Preferably the base 4 of the intermediate tubular portion 3 is flat, while the opposite wall 5 of said tubular portion is trough-shaped and provided with laterally projecting wings 6 and 7, respectively, of substantially inverted L-cross section that connect into the longitudinal edges of the flat base 4. Thus, the cross section of the tubular portion 3 as illustrated in Figure 5 provides the maximum strength both vertically and horizontally thereof.

The flattened end portions 1 and 2 are flared slightly as shown and have two flat plies 8 and 9, respectively. In this connection it will be noted that the marginal portions 10 and 11, respectively,

of the flat plies 8 are separated slightly to provide slots 12, while holes 13 are provided in the flat plies 9. Thus, when the support A is bent longitudinally as shown in Figure 2 to conform to the cross sectional configuration of a vehicle body top, suitable securing elements (not shown) may be engaged with the holes 13 to fasten the support in place.

In the process of construction the support A is formed by first rolling a sheet of metal into tubular form corresponding in cross section to the intermediate portion 3. Predetermined lengths of such tubing are then cut whereupon opposite ends of such lengths are flattened as shown. Following this, the end portions are pierced to provide the holes 13 and are trimmed or otherwise finished so as to provide a smooth and neat structure. The lengths so formed are then bent longitudinally to conform to the cross sectional curvature of the vehicle top so that they may be readily secured in place.

In practice the intermediate portion 3 of such support is received within the downwardly opening channel of a crossbar or bow (not shown) of the top of the vehicle body, while the end portions 1 and 2 of the support extend downwardly beyond the ends of said crossbar and are fastened to the vehicle body at opposite sides thereof. Preferably fabric sleeves (not shown) are slipped onto the intermediate portion 3 of each support before the latter is attached to the vehicle body so that the head lining (not shown) constituting the interior trim of the vehicle body top may be stitched or otherwise secured to the fabric sleeve on the support.

What I claim as my invention is:

1. The method of making for a vehicle body top a head lining listing support having a tubular body portion of substantially T-cross section and attaching portions constituting flattened endwise extensions of said body portion, the stem of the T being channel-shaped and provided throughout its length at the side edges of the channel with substantially flat laterally projecting flanges, the transverse portion of the T being substantially flat and spanning the channel throughout its length, said transverse portion being pressed firmly in surface-to-surface relation against the lateral flanges aforesaid so that the transverse portion cooperates with the side edges of the channel to form a circumferentially closed tube and cooperates with the flanges to provide laminated webs at opposite sides of the tube, including the steps of first rolling a sheet of metal to form the channel-shaped stem 55

and lateral flanges and the transverse portion spanning said channel-shaped stem and to cause the transverse portion to be positioned in surface-to-surface relation against the lateral flanges to 5 form the circumferentially closed tube and laminated webs aforesaid, then cutting the structure so formed into predetermined lengths, then flattening the channel-shaped portion between and substantially into alignment with the lateral flanges 10 at opposite ends of each length and to cause sections of the transverse portion at opposite ends of each length to be spread laterally apart, then piercing the flattened portions just mentioned between the laterally spaced sections 15 of the transverse portion to provide holes for securing elements, and finally bending longitudinally without distortion each length to a predetermined curvature to conform to the cross sectional curvature of a vehicle body top.

2. The method of making for a vehicle body top a head lining listing support having a tubular body portion of substantially T-cross section and attaching portions constituting flattened endwise extensions of said body portion, the stem 20 of the T being channel-shaped and provided throughout its length at the side edges of the channel with substantially flat laterally projecting flanges, the transverse portion of the T being substantially flat and spanning the channel 25 throughout its length, said transverse portion being pressed firmly in surface-to-surface relation against the lateral flanges aforesaid so that the transverse portion cooperates with the side edges of the channel to form a circumferentially closed tube and cooperates with the flanges to 30 provide laminated webs at opposite sides of the tube, including the steps of first rolling a length of sheet metal to form the channel-shaped stem and lateral flanges and the transverse portion 35 spanning said channel-shaped stem and to cause the transverse portion to be positioned in surface-to-surface relation against the lateral flanges to form the circumferentially closed tube and laminated webs aforesaid, then flattening the channel-shaped portion between and substantially into alignment with the lateral flanges 40 at opposite ends of the body and to cause sec-

tions of the transverse portion at opposite ends of the body to be spread laterally apart, then piercing the flattened portions just mentioned between the laterally spaced sections of the transverse portion to provide holes for securing elements, and finally bending longitudinally without distortion the tubular body portion to a predetermined curvature to conform to the cross sectional curvature of a vehicle body top. 5

3. The method of making for a vehicle body top a head lining listing support having a tubular body portion of substantially T-cross section and attaching portions constituting flattened endwise extensions of said body portion, the stem of the T being channel-shaped and provided throughout its length at the side edges of the channel with substantially flat laterally projecting flanges, the transverse portion of the T being substantially flat and spanning the channel 15 throughout its length, said transverse portion being pressed firmly in surface-to-surface relation against the lateral flanges aforesaid so that the transverse portion cooperates with the side edges of the channel to form a circumferentially closed tube and cooperates with the flanges to 20 provide laminated webs at opposite sides of the tube, including the steps of first rolling a length of sheet metal to form the channel-shaped stem and lateral flanges and the transverse portion 25 spanning said channel-shaped stem and to cause the transverse portion to be positioned in surface-to-surface relation against the lateral flanges to form the circumferentially closed tube and laminated webs aforesaid, then flattening the channel-shaped portion between and substantially into alignment with the lateral flanges 30 at opposite ends of the body and to cause sections of the transverse portion at opposite ends of the body to be spread laterally apart, then piercing the flattened portions just mentioned 35 between the laterally spaced sections of the transverse portion to provide holes for securing elements, and finally trimming the body and attaching portions to provide a smooth and neat structure. 40
